UNITED STATES PATENT OFFICE.

MAX HIMOFF, OF NEW YORK, N. Y.

RADIAL DRILL-PRESS.

1,032,408.

Specification of Letters Patent. Patented July 16, 1912.

Application filed July 22, 1909. Serial No. 508,911.

To all whom it may concern:

Be it known that I, MAX HIMOFF, a citizen of the United States, and resident of New York city, borough of Manhattan, in the county of New York and State of New York, have invented certain new and useful Improvements in Radial Drill-Presses, of which the following is a specification.

The object of my invention is to provide a drill press with means for permitting adjustment of the drills both radially and circularly with respect to their axes in such manner that adjacent drills may be brought as near together as the radii of their chucks 15 and supports will permit, the drills also being permitted to be moved radially of their axes rearwardly to a point approximating the location of the supporting column, whereby increased efficiency of the press 20 may be attained.

My invention comprises the novel details of improvement and combinations of parts that will be more fully hereinafter set forth and then pointed out in the claims.

Reference is to be had to the accompanying drawings forming part hereof; wherein, Figure 1 is a front elevation of a multiple radial drill press embodying my invention, parts being removed; Fig. 1^a is a detail view, in section, of column 3; Fig. 2 is a side elevation thereof partly in section; Fig. 3 is an enlarged detail sectional view showing means for securing the drill support to its column in adjusted position; Fig. 4 is a detail section on the line 4, 4, in Fig. 3; Fig. 5 is a detail section of the drill raising and lowering devices; Fig. 6 is a perspective view of a drill retaining member; and Fig. 7 is a sectional detail of 40 the drill controlling devices.

Similar numerals of reference indicate corresponding parts in the several views.

The numeral 1 indicates a suitable base provided with a table 2 for the work adapted to be raised and lowered and held in set position in any well known manner. Upon base 1 is supported any suitable number of columns 3 upon which the drills and their immediate operating devices are supported. 45 As the devices for supporting and adjusting the drills are similar for each column 3 it will suffice to describe one such set of devices as follows:—Upon column 3 a sleeve 4 is mounted for rotative adjustment, which 55 sleeve rests upon a suitable shoulder 5 on column 3. Means are provided for locking

sleeve 4 in set position, for which purpose I have shown a cone 6 receiving column 3, the tapering surface of which cone is adapted to enter a tapering recess or seat 4^a formed in the upper end of sleeve 4, a key 7 fitted in column 3 and entering a groove 6^a in cone 6 locking said cone against rotation upon column 3, but permitting said cone to have longitudinal adjustment upon 60 said column. At 8 is a nut fitting threads 9 on column 3 and adapted to be set against cone 6, whereby when the latter is thus forced into seat 4^a, when sleeve 4 has been adjusted to the desired angular position, 70 said sleeve will be held rigidly in such position. Sleeve 4 supports the drill holding and adjusting devices which are mounted upon said sleeve to have radial adjustment. For this purpose I have shown a suitable 75 arm or block 10 mounted to slide upon a projection 11 carried by sleeve 4, the arm 10 and projection 11 shown having dovetailed ways between them. A gib 12 may be provided between the parts 10 and 11, and set 80 screw 13 acting upon said gib may hold said parts in set position. Arm 10, at its forward end, has suitable bearings for the drill spindle 14 which revolves in the usual rack member 15 with which rack the gear 85 16 meshes. The shaft of said gear is shown supported by arm 10 and provided with an angular socket 17 (see Fig. 2) adapted to receive a correspondingly angular shank of an operating handle 18 for raising and 90 lowering the drill in wellknown manner. For the purpose of holding the drill in set position, as when the table and work are raised to the drill, I provide a suitable series of holes 19 in the metal surrounding 95 socket 17, and provide a handle 20 with a shank 21 adapted to fit socket 17, which handle 20 is provided with one or more holes 20^a to receive a pin adapted to enter holes 19, whereby the drill may be raised and 100 lowered and held in set position. I have shown the rack member 15 as normally held raised by a weight 22 having a cord or the like 23 passing over pulleys 24 on block 10 and attached to rack member 15, a suitable guide 25 carried by block 10 being adapted to guide the weight 22. Spindle 14 is connected by a telescopic shaft 26 with spindle 27, suitably interposed universal joints 28, 28^a connecting the parts 14, 26 and 27 for rotating spindle 14. The lower joint 28 connects with a spindle 14^a jour-

naled in bearing 10^a and provided with a bore 14^b in which spindle 14 slides as chuck A is raised and lowered, a key 14^c and groove 14^d between parts 14 and 14^a permitting sliding of the spindle 14 as it is rotated by spindle 14^a. Spindle 27 is journaled in a suitable bearing 29 carried by a frame 30 secured on columns 3, a pulley 31 on spindle 27 receiving a belt 32 from pulley 33 journaled on frame 30, the sleeve of pulley 33 being connected with a pulley 34 receiving belt 35 from drive pulley 36 shown supported by base 1.

For the purpose of providing accurate adjustment of arms 10 and for convenience in making such adjustment I provide a threaded rod or screw 40 shown journaled in a bearing 41 on arm 10 and provided with collars 42 on opposite sides of the bearing, the screw 40 meshing in suitable threads or a nut in a transverse aperture 43 in sleeve 4 (Fig. 3), whereby when screw 40 is rotated the corresponding arm 10 will be adjusted radially of sleeve 4 with respect to column 3 and held in set position by screw 40, or by the further aid of screw 13. Screw 40 is provided with a head 44 having suitable scale indications thereon, as in the nature of a gage to co-act with a pointer 45 or the like extending from sleeve 4, whereby the desired adjustment of arm 10 may be gaged. Head 44 may be detachably connected with screw 40 so as to be removed to prevent interference when adjacent sleeves are rotated toward each other.

With the parts arranged as set forth either of the sleeves 4 may be adjusted rotatively to the desired position and so held, and the corresponding arm 10 may be adjusted in a line parallel to a tangent of a circle described around the axis of the column or the sleeve and held in such position, the telescopic shaft 26 permitting such adjustments; and one or more of the drills 45 may be rotated as required. The feeding of the drills is effected in a well-known manner, or when the drills are set to definite positions the table may be raised to push the work against the drills. Arm 10 is so arranged at one side of column 3 that said block may be pushed rearwardly so far that the drill may be brought back substantially on a line with column 3, or arm 10 may be pushed outwardly to the limit of the capacity of the parts and so held, and by ro-

tatively adjusting sleeve 4 a large radius of drill operation may be effected. Furthermore, the arrangement is such that two adjacent drills may be adjusted as close together as their chucks and chuck supports 60 will permit without interference from the arms 10 which do not project forwardly beyond the drills, thereby leaving a wide space within which the drills may be adjusted. The arrangement therefore provides increased capacity of multiple radial drill presses, as known to me, for drilling holes relatively close together in the work, as well as for general drilling.

Changes may be made in the details of construction and arrangements set forth, within the scope of the appended claims, without departing from the spirit of my invention.

Having now described my invention what I claim is:

1. A drill press comprising a column, a sleeve journaled thereon, a cone mounted upon said column and adapted to co-act with said sleeve, means to cause said cone 80 to lock said sleeve to said column, and drill operating devices adjustably carried by said sleeve.

2. A drill press comprising a column, a sleeve journaled thereon and provided with a seat, a cone surrounding the column adapted to co-act with said seat, a key between said column and cone, a nut on a threaded portion of said column to act on said cone, and drill operating devices carried by said sleeve.

3. A drill press comprising a column, an arm, means for adjusting said arm with respect to said column, drill operating devices carried by said arm and comprising a rack and gear, the material adjacent said gear having a plurality of holes disposed around the axis of said gear, and a handle having means for detachable connection with said gear and provided with one or more holes 100 for holding said gear and rack in set position.

Signed at New York city, in the county of New York, and State of New York, this 21st day of July, A. D. 1909.

MAX HIMOFF.
